UNITED STATES PATENT OFFICE.

WILLIAM W. WALTERS, OF ROCHESTER, NEW YORK.

PEN AND PENCIL HOLDER.

Application filed February 6, 1925. Serial No. 7,283.

To all whom it may concern:

Be it known that WILLIAM W. WALTERS, a citizen of the United States, residing at Rochester, in the county of Monroe and State of New York, has invented certain new and useful Improvements in Pen and Pencil Holders, of which the following is a specification.

The object of this invention is to provide a new and improved pencil and pen holder that can be inserted into a pocket and securely fastened therein with the pencils and pen held in place in the holder.

These and other objects of this invention will be fully illustrated in the drawing, described in the specification and pointed out in the claims at the end thereof.

In the accompanying drawing:

Figure 1 is a perspective view of the pencil and pen holder.

Figure 2 is a detailed perspective view of the case of the pencil and pen holder.

Figure 3 is a detailed perspective view partly broken of the clamping or friction device for holding the pencils and pen in place in the holder.

Figure 4 shows detailed perspective views of a pair of the spring fingers of the clamping device.

In the several figures of the drawing like reference numerals indicate like parts.

The pencil and pen holder forming the subject matter of my present invention is made up of an elongated metal casing 1 having a cross section that will readily fit into a pocket. On one side of this casing, near the top thereof, is struck up from the inside an elongated blister 2 having an opening leading into it at each end thereof. A locking pin such as is used for fastening fraternity pins etc. to the coat is used for fastening the pencil and pen holder to the pocket into which the holder is inserted. Made to telescope into the casing and held in frictional contact with the inner wall thereof is the sleeve 3. This sleeve carries the spring fingers 4 and 5. Each of these fingers is made up of flat spring stock and two of them are joined together at their middle. This is done by forming a semicircular groove 6 across the middle of the spring finger 4 and cutting out a central portion of this groove to receive the semicircular lug 7 formed on the other spring finger 5. When the two fingers are brought together in this manner

a pin 8 is passed thru the circular opening formed by the groove 6 and lug 7 of the spring fingers so as to lock them together at their middle as illustrated in Figure 3.

The spring fingers are thus divided into two bow shaped sections with the ends of one finger making contact with the ends of the adjacent finger. A pair of these spring fingers 4 and 5 thus form a yielding partition and a number of such partitions may be inserted into the sleeve 3 to divide the interior of the sleeve into a number of compartments into which the pencils and pen may be inserted. The spring fingers are held in place in the sleeve by the pins that connect each pair of them by extending these pins in the wall of the sleeve 3.

The pins engage near the lower end of the sleeves and thus space the spring fingers only at that point. Near the top of the sleeve small indentations 9 are provided in the sleeve that are made to project between each pair of spring fingers and these indentations space the spring fingers near the top of the sleeve and prevent their swinging out of their vertical position. The inside of the sleeve is thus divided into a series of vertical parallel sections that are partially closed by the outwardly bulging spring fingers 4 and 5. When, therefore, a pen or pencil is inserted into one or more of the sections within the sleeve the bow shaped springs are slightly straightened by the pressure of the pencil or pen that is inserted between the spring fingers or between the end of the sleeve and one of the spring fingers. The reaction of the spring then grips the pencil and pen and holds it firmly in position in the sleeve. The pen or pencil may thus be inserted into the holder to any desired depth and the spring fingers will hold it suspended in place therein so that it cannot drop out of the holder or settle down to the bottom of the holder where the point of the pencil may be broken off or the pen point of the pen be damaged.

I claim:

2. In a pencil and pen holder, the combination of a casing, a sleeve adapted to telescope into said casing, a pair of spring fingers mounted transversely within said sleeve forming a partition within said sleeve, said pair of spring fingers being locked together and bulging out in either

direction to form yielding friction members that decrease the space of the sections formed by the partitions.

2. In a pencil and pen holder, the combination of a casing, a sleeve adapted to telescope into said casing and be held in place within said casing by frictional contact therewith, a pair of spring fingers mounted within said sleeve, each of said 10 pair of spring fingers having a semi-circular depression formed therein, said depressions being adapted to be lined up with each other, a pin carried by said sleeve and adapted to pass thru said depressions in said pair of fingers to lock said pair of fingers together at their middle thereof.

3. In a pencil and pen holder the combination of a casing, a sleeve adapted to telescope into said casing and be held in 20 place within said casing by frictional contact therewith, a pair of spring fingers mounted within said sleeve, each of said pair of spring fingers having a semicircular

depression formed therein, said depressions being adapted to be lined up with each 25 other, a pin carried by said sleeve and adapted to pass thru said depressions in said pair of fingers to lock said pair of fingers together at their middle thereof, each of said pair of springs bulging out 30 above and below their common fastening points within said sleeve to form a pair of yielding friction points on each side of the partition formed by said pair of springs.

4. In a pencil and pen holder, the combination of a casing, a sleeve adapted to telescope into said casing, spring fingers supported within said sleeve and forming transverse partitions therein, a blister formed in said casing near the top thereof, 35 said blister having openings at each end thereof to permit the insertion of a locking pin to hold said casing in place in a pocket.

In testimony whereof I affix my signature.

WILLIAM W. WALTERS.
